PORTABLE ELECTRIC LAMP

Robert Eugène Hochon, Neuilly-sur-Seine,
France

Application April 22, 1933, Serial No. 667,386

7 Claims. (Cl. 240—11.4)

The present invention relates to a portable electric lamp by means of which one may obtain the extinguishing, normal illumination or dimming (night-lamp effect) of the light by simply 5 turning the casing enclosing the glow lamp bulb.

This invention consists in the combination of casing, an electric glow lamp bulb and a multiple switch operating by gravity. The switch permits the complete extinguishing of the bulb, or the 10 possibility of lighting it to various degrees of intensity by the insertion in the feeding circuit of the bulb of a full or partial electrical resistance.

The casing is so constructed as to permit it to 15 remain steady in various positions. The switch forms part of the casing and is so constructed as to permit the lighting of the lamp in the varied positions taken by the casing, one of these positions marking the complete extinguishing of 20 the lamp.

The electrical current supply of the lamp may 25 be furnished by a local electrical source or by a lighting network. The current may either be continuous or alternating because of the use of a resistance regulating the light of the lamp.

At least one side or face of the casing permits the light to shine outside either by transparency or by diffusion. The most preferred form is that 30 of a parallelepiped, for example, a cube which may be placed on any of five faces, while the sixth permits the light to shine through.

The preferred switch operating by gravity is of the mercury type.

The attached drawing, and the following description 35 describe, by way of example, one embodiment of a portable electric lamp according to this invention.

Fig. 1 shows a type of lamp realized by means of a cubic casing.

Fig. 2 is a diagram of the connections of the 40 lamp with the representation in section of a typical gravity switch.

Fig. 3 shows a section perpendicular to the preceding section of this switch.

Fig. 4 relates to a cover permitting the use of 45 the lamp for photographic work.

In the lamp illustrated in Fig. 1, the cubic casing 1 has a frontal face 2 that permits the light to shine through. This face has a glass 50 wall that may either be transparent or translucent. The casing may be placed indifferently on one of its four lateral sides or on the bottom side 3.

The bottom 3 serves as a support for the bulb 4, for the switch 5 and for the resistance 6. Conductors 7 and 8 conduct the current from the

source of electrical energy to the bulb 4, and to the switch 5.

One of the terminal contact pieces of the switch is directly connected with the bulb 4 for normal illumination. Another terminal is connected 60 with the extremity of the resistance for dimming (night-lamp effect). A third terminal is connected with an intermediate point of the resistance for an intermediate light effect (Fig. 2).

The switch 5 (Figs. 2 and 3) comprises a conical cap of insulating material 9, such as ebonite, closed by a plate of conductive material 10. At the periphery of this cap 9 are placed contact pieces 11, for example, three contact pieces in a cubical casing. A fourth contact 12 may be 70 placed at the top of the conical cap to permit the realization of diffused lighting. In the interior of the enclosure formed by the cap 9 and the plate 10 may be rolled a blob of mercury 13 making an electrical connection between the 75 plate 10 and, successively, with each of the contacts 11 and 12. The switch is so constructed as to permit the contact pieces to be covered by the blob of mercury when the casing lies on one of its sides. The plate 10 has a projection at 80 the centre so as to permit the blob of mercury to close the circuit of the contact piece 12.

The resistance 6 is noninductive so as to permit the use of either continuous or alternating current. One practical embodiment consists in making it in the form of a stick of graphite or carbon, contact being made at any point by means of metal rings 14.

This invention may be used in photographic work. For this purpose an opaque cover 15 90 (Fig. 4) is placed on the illuminating surface 2 of the cubical casing 1. This cover has an opening 16 that is generally circular. This opening is shut off by means of a device that permits the passage of one colour only, red for example, or green or yellow according to the nature of the work. A single plate of a given colour may be used, or two transparent plates 17 and 18 between which an appropriate coloring matter, such as an inactinic paper, like Virida is placed.

What I claim is:

1. A portable electric lamp comprising a casing that may be placed on five of its faces with a sixth face that permits the passage of light, an electric bulb that may be illuminated and a resistance placed inside the casing, the said resistance having the form of a stick and including several contacts made by metallic collars surrounding the stick, means of connecting the bulb with a source of electrical energy, and a switch operating by 110

gravity forming part of the casing in order to control the bulb's circuit and to produce, by means of the resistance, various degrees of illumination in the bulb according to the position of the casing.

2. A portable electric lamp comprising a casing that can be placed in various steady positions by turning from one side to another and having at least one side through which a light may shine, 10 an electric bulb that may be illuminated and a resistance placed inside of the casing, means of connecting the bulb with a source of electrical energy and a switch comprising an insulated conical cap closed by a plate of conductive material 15 to which is attached one of the conductors carrying the current, contact pieces placed inside the conical cap, one of the contact pieces being electrically connected with the bulb, and the others by the intermediary of the resistance, a blob of 20 mercury that establishes the electrical liaison between the plate and each of the contact pieces successively, according to the position in which the casing is placed, thus permitting the extinction of the lamp as well as obtaining the various degrees of light intensity in the bulb.

3. A portable electric lamp comprising a cubic casing that may be placed on five of its faces with a sixth face that permits the passage of light, an electric bulb that may be illuminated and a resistance placed inside of the casing, means of connecting the bulb with a source of electrical energy, and a switch comprising an insulated conical cap, closed by a plate of conductive material and having at its centre a projection in the 35 interior, the said plate being connected with a conductor carrying the current, contact pieces, one of which is placed at the centre, and others in the periphery of the cap, and connected with the bulb, some directly and others by means of 40 the resistance, and a blob of mercury establishing an electrical liaison between the plate and each of the contact pieces, according to the side on which the casing has been placed, and permitting the extinction of the lamp as well as obtaining the 45 various degrees of light intensity in the bulb.

4. A portable electric lamp for photographic work comprising a casing movable in various positions by turning from one side to another and having a single lighting surface, an opaque cover placed over the said surface, and having an aperture so arranged as to permit the passage of but a single color, an electric bulb that may be illuminated and a resistance placed inside of the casing, means of connecting the bulb with a source of electrical energy, and a switch operating by gravity forming part of the casing in order to control the bulb's circuit and to produce, by means of the resistance, various degrees of illu-

mination in the bulb according to the position of the casing.

5. A portable electric lamp for photographic work comprising a casing movable in various positions by turning from one side to another and having a single lighting surface, an opaque cover placed over the said surface, and having an aperture provided with a colored glass that permits the passage of but a single color, an electric bulb that may be illuminated and a resistance placed inside of the casing, means of connecting the bulb with a source of electrical energy and a switch operating by gravity forming part of the casing in order to control the bulb's circuit and to produce, by means of the resistance, various degrees of illumination in the bulb according to the position of the casing.

6. A portable electric lamp for photographic work comprising a casing movable in various positions by turning from one side to another and having a single lighting surface, an opaque cover placed over the side surface, and having an aperture provided with two sheets of colorless glass, a sheet of colored material placed between the said sheets of colorless glass for permitting the passage only of a given color, an electric bulb that may be illuminated and a resistance placed inside of the casing, means of connecting the bulb with a source of electrical energy, and a switch operating by gravity forming part of the casing in order to control the bulb's circuit and to produce, by means of the resistance, various degrees of illumination in the bulb according to the position of the casing.

7. A portable electric lamp comprising a casing that can be placed in various steady positions by turning it from one side to another and having at least one side through which light may shine, an electric bulb that may be illuminated and a resistance placed inside of the casing, the said resistance having a number of branching points, means for connecting the bulb with a source of electrical energy and a switch operating by gravity fixed inside the casing, the said switch comprising an insulated conical cap closed by a plate of conductive material to which is attached one of the conductors carrying the current, contact pieces placed inside the conical cap and connected with the branching points of the resistance, some of the contact pieces being also connected with the bulb, and a blob of a weighty liquid that establishes the electrical connection between the plate and any contact piece according to the position in which the casing is placed, thus permitting the extinguishing of the lamp as well as obtaining the various degrees of light intensity in the bulb.
